PARTITION SUPPORTING CLIP

Ford M. Thomas, Bristol, Vt., assignor to Vermont
Box Co., Inc., Bristol, Vt., a corporation of Ver-
mont

Application January 25, 1950, Serial No. 140,402

1 Claim. (Cl. 24—73)

1

The present invention relates to partition supporting clips for store counters and embodies, more specifically, an improved form of clip by means of which partitions may be supported in the desired positions upon store counters and, at the same time, providing facility for utilizing a bottom member that rests upon the counter and extends entirely to the edges thereof without interference by the clip.

In existing forms of clips of this character, the post portion of the clip that is adapted to be inserted in suitable apertures in the counter normally interferes with the use of a bottom layer that rests upon the counter and completely covers the same, because the bottom layer cannot extend beyond the line in which the clip post lies. In accordance with the present invention, it is an object to provide a clip of the above character wherein bottoms may be utilized on counters in such fashion as to occupy the entire space comprising the bottom of bins formed by partitions supported on the counter by means of counter clips, as aforesaid.

Further objects of the invention will be apparent as it is described in greater detail in connection with the accompanying drawings, wherein:

Figure 1 is a perspective view of a portion of a counter having a plurality of partitions supported thereon by means of clips constructed in accordance with the present invention, and in which a bottom member is utilized;

Figure 2 is a view in section, taken on the plane indicated by the line 2—2 of Figure 1, and looking in the direction of the arrows;

Figure 3 is a view in section, taken on the line 3—3 of Figure 2, and looking in the direction of the arrows; and

Figure 4 is a plan view of the outline of a clip constructed in accordance with the present invention prior to the forming operation.

Referring to the above drawings, a counter or counter sham is shown at 10 and is provided with a longitudinal partition 11 and a plurality of transverse partitions 12. Supported upon the counter or sham 10 is a bottom plate 13, which may be a mirror, colored film, or other composition over which the partitions 12 are supported. A plurality of clips 14 are provided to secure or maintain the partitions 12 in the desired positions, these clips comprising a back portion 15, partition supporting flanges 16, a vertical spacer 17, a horizontal spacer 18, and a supporting post 19. The posts 19 are adapted to be received in any of a plurality of holes 20 formed in the counter 10, as illustrated in Figures 2 and 3.

As illustrated in Figure 4, the clip 14 may be formed out of a blank by folding the same along the dotted lines 16' to form the spaced flanges 16, folding again at dotted line 17' and then again 5 along the line 18'. The post 19 is formed by curving or otherwise forming the bottom portion of the blank.

As illustrated in Figures 2 and 3, the vertical spacer 17 spaces the bottoms of the flanges 16 10 from the post 19 and thus provides a space within which a bottom plate 13 is received so that the latter covers substantially all of the counter or sham 10. The horizontal spacer 18 serves to offset the back of the clip portion 15 from the axis 15 of the post 19, in order that the edge of the bottom plate 13 may extend to the edge of the counter 10.

While the invention has been described with specific reference to the accompanying drawings, it is not to be limited save as defined in the appended claim.

I claim:

A partition-supporting clip for a counter having a removable bottom plate or sheet, said clip comprising a post adapted to be inserted in a hole in said counter, a back member having laterally extending substantially parallel partition-engaging flanges, and a substantially right angular supporting web joining said back member to said post, one leg of said web being fastened right angularly to said post and extending away from the said post sufficiently to permit said bottom plate or sheet to cover the same, and the other leg of said web being connected axially 30 to said back and extending away from said post 35 a distance at least equal to the thickness of said bottom plate or sheet.

FORD M. THOMAS.
